JOSEPH O. AMBERG, OF EAST ORANGE, NEW JERSEY

BELT BUCKLE

Application filed September 30, 1930. Serial No. 485,358.

This invention relates, generally, to belt buckles; and the invention has reference, more particularly, to buckles particularly adaptable for use in connection with military belts of the "Sam Browne type".

"Sam Browne" belts are used largely by military and naval officers for formal wear and it is essential, therefore, that these belts and their buckles should be highly attractive in appearance and should remain so during the life of the belt. Belts of this type, as heretofore generally constructed, become unattractive in appearance after slight use, not only because of the tendency of the portion 10 of the belt lying within the confines of the belt buckle to become distorted and to move or work rearwardly away from the face of the belt buckle and from the hook of the buckle, thereby causing the frame of the 15 buckle to stand out prominently in advance of the belt which is undesirable, but also because the repeated fastening and unfastening of the belt at the buckle abrades the finished forward surface of the belt.

The principal object of the present invention is to provide a novel belt buckle structure which is especially adapted for use on belts of the "Sam Browne" type, which buckle structure is so constructed and arranged as 20 to cause the belt and buckle to have a neat and attractive appearance over a long period of use, the said belt buckle structure having means for positively positioning that portion of the belt confined by the outlines of the 25 buckle forwardly so that the front surface thereof lies substantially flush with the buckle face.

Another object of the present invention lies in the provision of a novel belt buckle structure so constructed and arranged as to enable the easy and quick separation or parting of the belt associated therewith, without actually unfastening the belt from the prongs of the buckle, whereby that portion of the belt passing through the buckle always remains in fixed position with respect to the buckle frame and consequently does not have its finished-surface marred by the repeated fastening and unfastening of the belt.

Still another object of the present invention

lies in the provision of a belt buckle structure which is of simple, sturdy construction and which is easily applied to a belt.

Other objects of this invention, not at this time more particularly enumerated, will be 55 clearly understood from the following detailed description of the same.

The invention is clearly illustrated in the accompanying drawing, in which:—

Fig. 1 is a fragmentary view in front elevation showing a belt equipped with the novel buckle structure of this invention.

Fig. 2 is a top plan view of a portion of the structure shown in Fig. 1.

Fig. 3 is a view similar to Fig. 1 but with 65 parts broken away to better illustrate the invention.

Fig. 4 is a sectional view taken along lines 4—4 of Fig. 1.

Fig. 5 is a view similar to Fig. 3 but showing a slightly modified form of construction.

Fig. 6 is a view similar to Fig. 5 but showing another slightly modified form of construction; and

Fig. 7 is a view similar to Fig. 6 but showing a third modified form.

Similar characters of reference are employed in all of the above described views, to indicate corresponding parts.

Referring now to said drawing, the reference numeral 1 designates a belt which may be of the "Sam Browne" type, and which has a double row of eyelets 2 provided in the free end portion 3 thereof. Portion 3 of belt 1 is adapted to be passed through a buckle 4 and the eyelets 2 are adapted to engage the two vertically spaced prongs 5 of this buckle in the usual manner. The prongs 5 are of angular shape, the same having exposed portions which extend substantially parallel to the front face of the buckle frame 6 and angularly off-set rearwardly directed portions 7 (see Fig. 4) which extend through the eyelets 2 and have their rear ends integrally or otherwise secured to the vertical buckle stem 8. Buckle stem 8 is rearwardly offset slightly from the plane of buckle frame 6 and has its ends pivotally mounted 90 in bearing apertures provided in lugs 9 100

formed at the rear of the upper and lower transverse portions of the buckle frame 6.

When the belt 1, having the buckle 4, is first worn by the wearer, the belt end portion 3 is initially threaded through the buckle and the pair of eyelets 2 which best suit the wearer's girth dimension are engaged over the prongs 5. The buckle structure is so designed that thereafter, the releasing or parting of the belt is accomplished by other means than by unfastening the belt end portion 3. Also, the novel buckle structure provides for the fastening of the belt without the necessity of manipulating the end portion 3.

To provide for the normal fastening and unfastening of the belt, a hook member is employed which has an apertured vertically disposed shank 11 connected to the other end 20 of belt 1. The end portion of the belt extends through the apertured shank 11 and is doubled back upon the belt and sewn thereon as by stitches 12, thereby forming a bight 10. Spaced U-shaped hooks 13 have their 25 rear portions or legs formed integral with the shank 11 and their front portions or legs extending substantially parallel and in forwardly spaced relation to their rear legs. The hooks 13 are adapted to releasably engage the buckle stem 8 intermediate the prongs 5 for the purpose of fastening the belt. With the belt end portion 3 threaded into desired position through the buckle 4, to 30 fasten the belt, it is merely necessary to cause hooks 13 to engage the buckle stem 8. Similarly, to unfasten the belt it is merely necessary to push shank 11 of the hook member toward the buckle stem 8 so that hooks 13 will disengage this buckle stem.

With the hooks 13 engaged over buckle stem 8, as shown in Fig. 4, the front legs of these hooks extend substantially parallel to the main run of the belt 1 and the forward surface of these legs press against the rear surface of that portion of the belt which is contained within the confines of the buckle frame 6 and serves to position the forward surface of this portion of the belt substantially flush with or slightly forwardly of the front face of the buckle frame 6, thereby causing the belt and buckle to have a neat and attractive appearance. Were the hooks 13 not present or otherwise disposed, the run of the belt passing through the buckle would tend to straighten out so that the portion lying within the confines of the buckle frame would move rearwardly, thereby allowing the belt buckle to project forwardly of the belt, creating an unattractive appearance.

In use, the belt is first applied to the wearer and the free end portion 3 thereof is adjusted through the buckle so that the proper eyelets 2 are engaged by the prongs 5. In passing the portion 3 through the belt buckle, the front legs of the hooks 13 serve to guide

the end portion 3 so that it will take up the position shown in the figures with that part of the belt within the confines of the belt buckle extended forwardly and substantially flush with the front face of the belt buckle frame 6. Once the free end portion 3 has been adjusted, as desired, this portion need never be removed from the belt buckle and the belt may be disconnected by disengaging the hooks 13 from the buckle stem 8. This is easily accomplished by moving the shank 11 toward the stem 8. Since the connection of buckle 4 with the free end portion 3 is never disturbed, and since the front legs of the hooks 13 serve to retain that portion of the belt lying within the confines of the buckle frame substantially flush with the outer face of the buckle, the belt and buckle always present an attractive appearance.

It will be apparent that the hook member may be formed in various ways. For example, in Fig. 5 this hook member is formed with a solid vertically extending shank 14 that is positioned within the bight 10 of belt 1 and has its prongs 13 projecting through apertures provided in the end wall of this bight. In Fig. 6 the hook member 15 is made by deforming a single wire or bar into a shape substantially similar to that of the hook member of Figs. 1 to 4, thereby providing the hooks 18 for engaging the stem 8 intermediate prongs 5. In Fig. 7, the hook member 16 is also made by deforming a single wire or bar into the shape shown in this figure. The hooks 19 of hook member 16 are arranged to engage stem 8 adjacent the pivotal connections of this stem with the frame 6. Hooks 19 have angular offset portions 17 for engaging the rear surface of that portion of the belt lying within the confines of the frame 6 to thereby hold such portion forwardly of the buckle stem.

It will be noted that the novel buckle structure of the present invention not only serves to position the belt forwardly within the buckle so that the same presents an attractive appearance, but also serves to provide additional fastening means other than prongs 5 for use in the normal fastening and unfastening of the belt.

As many changes could be made in the above construction and many apparently widely different embodiments of this invention could be made without departing from the scope thereof, it is intended that all matter contained in the above description or shown in the accompanying drawing shall be interpreted as illustrative and not in a limiting sense.

What is claimed is:—

1. A belt buckle structure comprising, a buckle frame, a buckle stem pivotally connected to said buckle frame, a buckle prong, said buckle prong having a forward exposed portion extending substantially parallel with

the front face of the buckle frame and a rearwardly directed portion, said rearwardly directed portion being secured to said buckle stem intermediate the ends of the latter, said 5 buckle prong cooperating with said buckle frame in holding a belt end portion threaded through said buckle, and a hook member adapted to be secured to the other belt end portion and having a hook for engaging said 10 buckle stem to thereby provide an additional means for fastening and unfastening the belt, said hook having the forward leg portion thereof extending substantially parallel to the front face of said buckle frame and being 15 pressed against the rear surface of that portion of the belt lying within the confines of said buckle frame, the forward exposed portion of said buckle prong cooperating with the forward leg portion of said hook whereby 20 such belt portion is held forwardly so that its front surface is substantially flush with the front face of said buckle frame.

2. A belt buckle structure comprising, a buckle frame, a buckle stem pivotally connected to said buckle frame and rearwardly offset therefrom, a pair of spaced buckle prongs having forward exposed portions extending substantially flush with the front face of the buckle frame and rearwardly directed portions, said rearwardly directed portions being secured to said buckle stem intermediate the ends of the latter, said buckle prongs cooperating with said buckle frame in holding a belt end portion threaded through 30 the buckle, a hook member having the shank thereof retained in a bight formed on the other belt end portion, a pair of spaced hooks formed on said hook member for engaging said buckle stem intermediate the prongs 35 thereof to thereby provide an additional means for fastening and unfastening the belt, the said hooks having their forward leg portions extending substantially parallel to the front face of said buckle frame and disposed to press against the rear surface of that portion of the belt lying within the confines of said buckle frame, the forward exposed portions of said buckle prongs cooperating with the forward leg portions of said hooks 40 whereby such belt portion is held forwardly so that its front surface is maintained substantially flush with the front face of said buckle frame.

3. A belt buckle structure comprising, a buckle frame having pivotal bearing lugs formed at the rear thereof, a buckle stem having its ends journaled in said bearing lugs, a pair of buckle prongs having forward portions for engaging said buckle frame and 55 singularly offset rearwardly directed portions secured to said buckle stem, said buckle prongs being arranged to cooperate with a belt end portion threaded through said buckle frame, a hook member having a shank secured 60 in a bight formed on the other belt end portion 65

and a pair of hooks formed on said shank for engaging said buckle stem to provide an additional means for fastening and unfastening the belt; the said hooks having their forward leg portions extending substantially parallel to the front face of said buckle frame and disposed to press against the rear surface of that portion of the belt lying within the confines of said buckle frame, said forward portions of said buckle prongs being formed for cooperating with the forward leg portions of said hooks in such a manner whereby such belt portion is held forwardly so that its front surface is substantially flat and positioned flush with the front face of said buckle frame.

In testimony, that I claim the invention set forth above I have hereunto set my hand this 23rd day of September, 1930.

JOSEPH O. AMBERG.
